UNITED STATES PATENT OFFICE.

EDWARD O. PARKER, OF BROOKLYN, NEW YORK, ASSIGNOR TO HERMAN C. KUPPER, INC., OF NEW YORK, N. Y., A CORPORATION OF NEW YORK.

DESIGN FOR A CRUET.

Application filed June 9, 1924. Serial No. 9,836. Term of patent 7 years.

To all whom it may concern:

Be it known that I, EDWARD O. PARKER, a citizen of the United States of America, residing in the borough of Brooklyn, county of Kings, city and State of New York, have invented a new, original, and ornamental Design for a Cruet, of which the following is a specification, reference being had to the accompanying drawing, forming part thereof.

Fig. 1 is a front view of a cruet embodying the design; and Fig. 2 is a side view thereof.

I claim:

The ornamental design for a cruet as shown.

Signed at Brooklyn, county of Kings, State of New York, this 4 day of June, 1924.

EDWARD O. PARKER.
